US0D1065184S

(12) **United States Design Patent** (10) **Patent No.:** **US D1,065,184 S**
(45) **Date of Patent:** **** Mar. 4, 2025**

(54) **WEARABLE SMART DEVICE**

(71) Applicant: **HTC Corporation**, Taoyuan (TW)

(72) Inventors: **Chang-Hua Wei**, Taoyuan (TW);
Yu-Lin Huang, Taoyuan (TW)

(73) Assignee: **HTC Corporation**, Taoyuan (TW)

(**) Term: **15 Years**

(21) Appl. No.: **29/813,583**

(22) Filed: **Oct. 29, 2021**

(51) **LOC (15) Cl.** **14-02**

(52) **U.S. Cl.**

USPC **D14/344**

(57) **CLAIM**

The ornamental design for a wearable smart device, as shown and described.

DESCRIPTION

FIG. 1 is a top perspective view a first embodiment of a wearable smart device, in accordance with our new design; FIG. 2 is a front view thereof;

FIG. 3 is a rear view thereof;

FIG. 4 is a left view thereof;

FIG. 5 is right view thereof;

FIG. 6 is a top plan view thereof;

FIG. 7 is bottom plan view thereof;

FIG. 8 is a top perspective view a second embodiment of a wearable smart device, in accordance with our new design;

FIG. 9 is a front view thereof;

FIG. 10 is a rear view thereof;

FIG. 11 is a left view thereof;

FIG. 12 is right view thereof;

FIG. 13 is a top plan view thereof; and,

FIG. 14 is bottom plan view thereof.

The broken lines in the drawings depict portions of the wearable smart device that form no part of the claimed design.
